UNITED STATES PATENT OFFICE.

WILLIAM H. SCOTT, OF ST. LOUIS, MISSOURI.

BOLSTER.

SPECIFICATION forming part of Letters Patent No. 737,159, dated August 25, 1903.

Application filed May 16, 1903. Serial No. 157,353. (No model.)

To all whom it may concern:

Be it known that I, WILLIAM H. SCOTT, a citizen of the United States, residing at St. Louis, Missouri, have invented a certain new and useful Improvement in Bolsters, of which the following is a full, clear, and exact description, such as will enable others skilled in the art to which it appertains to make and use the same, reference being had to the accompanying drawings, forming part of this specification, in which—

Figure 1 is a top plan view of the major portion of a bolster embodying my invention. Fig. 2 is a side elevational view of the same. Fig. 3 is a longitudinal vertical section taken centrally through Fig. 1. Fig. 4 is a horizontal sectional view taken on the line 4-4 of Fig. 2. Fig. 5 is a vertical section taken on the line 5-5 of Fig. 2, and Fig. 6 is a fragmentary sectional view taken through the head-block substantially on the line of Fig. 3 with the parts separated for the purpose of better illustration.

This invention relates to new and useful improvements in bolsters comprising a compression member, a tension member, a strut, and sectional head-blocks, the object of the invention being to produce a bolster of the class described which will be economical in manufacture and which will provide for a positive locking of the parts in coöperative position.

Referring to the drawings, it will be noted that aside from the enlarged end 5 of the tension member the invention resides chiefly in the construction of the head-blocks, and as said blocks are duplicates but one is illustrated herein.

A is the upper section of the head-block, which is provided with a transversely extended seat 1, upon which rests the web portion of the compression member C, and seats 2 are provided for the flanges of said compression member. In the seat 1 is a laterally extended opening through which may be projected the bolt or rod 3, which is adapted to tie the compression member to said head-block. In the section A is a seat 4 for the enlarged end 5 of the tension member D, which enlarged end is held in position therein by the head-block section B, which latter is provided with spring-seats 6, the section B

resting within the lower hollow portion of section A and being provided with an inclined wall 7, upon which rests the tension member. The section A is provided with a lip or extension 8, adapted to extend over the end of the compression member C for the purpose of more securely locking the same in position.

The head-block sections are designed to be manufactured from malleable castings and are preferably cored out, as shown, so as to provide a proper section to permit of the use of such castings.

Having thus described my invention, what I claim as new, and desire to secure by Letters Patent, is—

1. In a bolster, a compression member, a tension member, hollow head-blocks, and a member adapted to rest therein upon which inner member said tension member is adapted to rest; substantially as described.

2. In a bolster, a compression member, a tension member with enlarged ends, a head-block with seats for said enlarged ends, and a member below said tension member, bearing against said tension member; substantially as described.

3. In a bolster, a compression member, a tension member with enlarged ends, a head-block with seats for said enlarged ends, and a member with inclined upper face below said tension member, bearing against said tension member; substantially as described.

4. In a bolster, a compression member, a tension member with an enlarged end, and a head-block provided with a seat for said compression member, which seat forms an abutment for the enlarged ends of said tension member; substantially as described.

5. In a bolster, a compression member, a head-block with a seat for the compression member, a seat in said head-block beyond the end of the compression member, adapted to receive the end of a tension member, a tension member with enlarged end portion, and a removable member adapted to lock said tension member in position; substantially as described.

6. In a bolster, a compression member, a tension member with enlarged end portions, head-blocks with seats for said enlarged ends, and spring-seat members adapted to lock said

tension member in position in said seats; substantially as described.

7. In a bolster, a hollow head-block with a seat, a tension member with enlarged end 5 adapted to rest therein, and a spring-seat member adapted to lock said tension member in position; substantially as described.

8. In a bolster, a compression member, a tension member, a strut, telescopic head-blocks, one of said head-blocks being provided with a seat for the compression member, and a seat for the tension member, and the other of said blocks being so formed as to hold said tension member in its seat; substantially as described.

9. In a bolster, the combination with a strut, a compression member, telescopic head-

blocks, and a tension member which is clamped between, and is retained by, said telescopic head-blocks; substantially as described.

10. In a bolster, the combination with a compression member, a tension member, and a strut, of telescopic head-blocks having faces which are complementary to the engaged faces of said tension member for securing the same 25 therebetween; substantially as described.

In testimony whereof I hereunto affix my signature, in the presence of two witnesses, this 14th day of May, 1903.

WILLIAM H. SCOTT.
